(57) **CLAIM**

The ornamental design for a slate computer, as shown and described.

DESCRIPTION

FIG. 1 is a top front perspective view of a slate computer showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear perspective view thereof showing that the present slate computer has both of its upper and lower stands unfolded; and,

FIG. 9 is a right side view thereof showing that the present slate computer has only its upper stand unfolded.

The broken lines depict portions of the slate computer that form no part of the claimed design.
